UNITED STATES PATENT OFFICE.

JOHN L. WAGNER, OF FAIRMONT, WEST VIRGINIA.

CABLE-HAUL.

SPECIFICATION forming part of Letters Patent No. 788,861, dated May 2, 1905.

Application filed June 16, 1904. Serial No. 212,906.

To all whom it may concern:

Be it known that I, JOHN L. WAGNER, a citizen of the United States, residing at Fairmont, in the county of Marion and State of West Virginia, have invented certain new and useful Improvements in Cable-Hauls, of which the following is a specification.

My invention relates to cable - hauls or similar systems in which interengaging devices are provided on cars and on an endless cable, whereby the cars are automatically picked up by the cable at one point and delivered to another point.

My invention consists in certain novel combinations of features and details of construction hereinafter fully described, and particularly pointed out in the claims, reference being made to the accompanying drawings, forming part of this specification, in which—

Figure 1 is a vertical sectional view of that portion of the system at which the cars are picked up by the cable. Fig. 2 is a similar sectional view of that portion of the system where the cars are released, suitable driving machinery for the cable being also suggested. Figs. 3 and 4 respectively show a vertical transverse section and a partial plan of braking mechanism automatically operated in the system for retarding the cars at the point where they are released by the cable. Figs. 5, 6, and 7 respectively show a side elevation of the interengaging devices on the car and cable, a bottom plan of the engaging device applied to the cars, and a top plan of the engaging device or trolley, of which a number are applied at suitable intervals on the cable. Figs. 8 to 11 illustrate further features of my invention, whereby the dogs are raised and held in elevated position prior to or upon entering the mine in order to avoid fouling with obstructions while the car is in the mine and released so that they can gravitate to engaging position when or after the car leaves the mine, Figs. 8 and 10 being, respectively, a side elevation and a bottom plan view of the car-dogs with the centrally-disposed rail for raising said dogs into engagement with suitable detents, and Figs. 9 and 11 being a side elevation and a bottom plan view, respectively, of the dogs with the laterally-disposed rails for releasing the detents.

Referring to Figs. 1 and 2, A represents a portion of the downwardly-inclined track leading from the point of delivery—for instance, the mouth of a mine-shaft; B, the portion of the car-track connecting with A where the cars are to be picked up by the cable, inclined upwardly to reduce the momentum of the cars, and C the portion of the track where the cars are discharged by the cable, usually given a slight downward incline in order that the cars will proceed by their own momentum after being released to a dumping-point—such, for instance, as a tipple. D represents any suitable type of driving machinery for the cable, which may conveniently be located adjacent to the dumping-point for the cars. When cars are discharged from the mouth of the mine, it is desirable to have them move off promptly, and for this reason the portion of the track A is given a considerable incline downward, and for this reason it is customary, even though the dumping-point is lower than the point B, to provide an incline at B sufficient to reduce the speed of the cars to what it should be. The cars are indicated by dotted lines at 5 and their wheels at 6. The engaging device carried by these cars is represented at 7 and comprises dogs 8 9, suitably pivoted beneath the car-body in a manner to permit them to gravitate into engaging position. The engaging devices on the cable comprise trolleys 4, running on suitable tracks and carrying blocks 10, in front of and behind which the dogs 8 and 9 drop for engagement. The distance between the dogs is such that when either dog is in engagement the other dog can swing upward out of engaging position. One feature of my invention consists in providing interengaging means on the cars and on the cable, comprising pivoted dogs on the cars, adapted to swing upward out of engaging position, and a block on the cable, in front of and behind which these dogs are adapted to engage, so as to confine the car relatively to the cable in both directions. Under some circumstances, particularly when the cars are light, it is desirable to have means for holding the cars on the track upon which they run. Another feature of my invention therefore consists in providing the blocks 10 with suitable undercuts 11, as shown by dot-

ted lines in Figs. 5 and 7, and the dogs 8 9 with projections 12, adapted to enter the undercuts 11, so that the interengagement of the devices 7 and 4 holds the cars down upon their tracks, the tautness of the cable being sufficient to prevent the trolleys 4 from yielding upward. When a car moves rapidly down the incline A, dog 9 will readily ride over the block 10 should the car overtake one of the trolleys 4 near the bottom of the incline B and when the car is moving at a much greater rate than the cable; but if the dog 8 should strike block 10 at such a time there is danger of either breaking some of the parts or derailing the car. Another feature of my invention consists, therefore, in providing between the delivery-incline and retarding-incline means for raising the rear dog on the car and holding it out of engaging position until such time as the momentum of the car is largely overcome and its rate of movement reduced to approximately that of the cable. One embodiment of such means is illustrated in the drawings as comprising a lifting-rail 13, arranged along the track with an inclined front end and in position to engage the rear dog or a part thereof—for instance, through the lateral projection or pin 18 on the dog. This lifting-rail will be to one side of the dogs or otherwise arranged so that it affects the rear dog only, and, as suggested by the breaking away of the end and its continuance in dotted lines, it may extend to any desired point, the front dog being allowed to hang in engaging position, so that the car will be picked up by the cable as soon as sufficiently retarded to be overtaken by one of the trolleys.

If the projections 12, entering the undercuts 11, are not used, the trolleys will naturally sink below the line of engagement with the dogs when the car reaches the position shown in Fig. 2, at which point the cable is below the surface of the track; but since it is preferable to have this interlocking of the dogs with the trolley it is necessary in order to release the dogs from the trolley to permit a disengaging relative movement between the trolley and the dogs engaged therewith by raising one of the dogs and then to cause such relative movement as will result in the remaining dog becoming disengaged. If the depression of the cable relatively to the track takes place on the upgrade, it is obvious that the front dog would be in engagement, and therefore that the rear dog would have to be raised previous to reaching such point of depression and thereafter the car accelerated relatively to the cable—as, for instance, by a slight downgrade in the track—just before the point of depression is reached, which would draw the projection 12 on the front dog out of the front undercut 11, after which the car is free to continue under its own momentum to the dumping-point; but if there is downgrade in advance of the point of de-

pression a sufficient distance to cause the rear dog to engage the trolley then it will be necessary to raise the front dog and to retard the car to unlock the rear dog just before the trolley drops below the plane of the track. 70 Another feature of my invention therefore consists in combining with the interengaging and interlocking means on the car and cable means for raising one of the dogs, so as to permit a relative disengaging movement between the trolley and the other dog, and means for causing this relative movement when the parts are in position to permit it to take place. The embodiment of this feature, which I have illustrated, is shown in Fig. 2 of the drawings, where the car is on the downgrade, and therefore has to be held back by the engagement of its rear dog with the trolley. The lifting-rail 13^a is on the opposite side of the dogs from the lifting-rail 13, previously described, and has lifted the dog 9 by its laterally-projecting pin 18^a (shown in dotted lines in Figs. 2 and 5 and in full lines in Fig. 6,) also an automatically-applied brake, which is more clearly understood upon reference to 80 Figs. 3 and 4, wherein 14 represents brake-shoes adapted to impinge the sides of the car-wheels. 15 represents thrust rods by which the shoes 14 are carried. 16 represents pressure-plates at opposite sides of the trolley-track, and 17 represents antifriction-rollers projecting from the sides of the trolley in position to impinge the plates 16 as the trolley passes between them to force the brake-shoes 14 against the wheels 6. By this construction, as will be seen, I provide not only automatic means for moving one dog out of engaging position to permit relative movement between the car and trolley in the direction of the raised dog and automatic means for 90 causing this relative movement to take place, but also means causing this relative movement to take place which is automatically actuated by the trolley and specifically a means for retarding the car automatically actuated by the trolley.

Rails 13 and 13^a, with their coöperating dogs, provide automatic means for lifting the dogs at suitable points along the tracks, said means being alternated on opposite sides of the track 105 and each dog being provided with its special engaging means, so that one dog may be affected independently of the other.

As is well known in the usual operation of single-cable hauls, the cable is used both 110 to run the cars out and to return them. I have only illustrated the outgoing track in my invention; but it is obvious that the principles here explained are applicable in returning the cars, and the lifting-rails and means 115 for releasing the dogs from their engaging positions that the trolley may be depressed may be located at any point where it is desirable to have the several functions of these parts performed.

There is a decided advantage for some purposes in having dogs mounted on the car instead of on the trolley, as proposed. This location of the dogs facilitates the use of means for controlling their positions and for moving them out of engaging position. Moreover, gravitating-dogs can be employed with very much less complication than when the dogs are mounted on the trolley. When the dogs are carried by the car and necessarily enter the mine with the car, they will be liable to meet obstructions of coal or other solid matter lying between the rails of the track, and thus be in danger of becoming broken. The same conditions may be encountered in other uses to which my cable-haul system is applicable. To avoid this danger, I provide further features of my invention, one of which consists of a centrally-disposed lifting-rail 19, having an inclined end 19^a, upon which the dogs 8 and 9 ride either before or immediately after the car enters the mine or enters upon any portion of the track where it may be desirable to hold the dogs in elevation or at some other suitable point, while detents 20, swinging in bearings 21 and having counterbalance-arms 22, are adapted to engage the pins 18 18^a on the dogs when the latter are raised up and hold said dogs in elevated position until the detents are released. In order to release the detents and permit the dogs to drop into engaging position after the car leaves the mine or reaches a portion of the track where it is desired to have the dogs or either of them in effective position, laterally-disposed releasing-rails 23 are put into position to lift the counterweight-arms 22 as they ride up on the incline 23^a, and thus permit the dogs 8 and 9 to drop. It will be understood that the rail 19 will be on the track by which the cars enter the mine, whereas the pair of rails 23 will be on the track by which the cars leave the mine. The exact points at which these rails are located may be selected according to the time in the passage of the car when it is desired to have the several functions performed. Obviously the rail on that side of the dogs which releases the rear dog can be located at a different point in the track from the rail which is utilized to release the front dog. The dog-releasing rail may often be located on the knuckle at the point at which it is desired to drop the rear dog behind the block on the cable, in which event the lifting-rail 13, heretofore described, need not be employed to prevent the rear dog from striking the cable-block before the momentum of the car has been overcome—that is to say, the detent for the rear dog and its releasing-rail together serve as the means for holding the dog elevated at the desired point and dropping it behind the block when the momentum of the car is overcome.

Having thus described my invention, what

I claim, and desire to secure by Letters Patent, is—

1. In a cable-haul, the combination with the cable and a car to be held thereby, of interengaging means carried respectively by the 70 car and the cable; said means on the car comprising depending pivoted dogs.

2. In a cable-haul, the combination with the cable and a car to be held thereby, of interengaging means carried respectively by the 75 car and the cable; said means on the car comprising depending pivoted dogs, and said means on the cable comprising a block in front of and behind which said dogs project when in their depending positions.

3. In a cable-haul, the combination with the cable and the car to be held thereby, of depending dogs on the car, and means on the cable in front of and behind which the dogs engage; said means on the cable and said dogs 85 being constructed to interlock against relative vertical movement when in engaging position.

4. In a cable-haul, the combination with the cable and the car to be held thereby, of depending dogs on the car, and a block on the cable in front of and behind which the dogs project; said dogs and block being constructed to interlock against relative movement in a vertical direction. 90

5. In a cable-haul, the combination with the cable and the car to be held thereby, of depending dogs on the car, and a block on the cable in front of and behind which the dogs project; said dogs and block being constructed 100 to interlock against relative movement in a vertical direction, and said dogs being spaced apart so that each is out of interlocking position when the other is in interlocking position. 105

6. In a cable-haul, the combination with the cable and the car to be held thereby; of depending dogs on the car and means on the cable in front of and behind which said dogs engage when in depending position; said means on the cable being provided with undercuts, and said dogs being provided with projections entering said undercuts to interlock the parts against relative vertical movement. 110

7. In a cable-haul, the combination with the 115 cable and the car; of interengaging means on the car and cable; said interengaging means on the car comprising depending dogs projecting in front of and behind the interengaging means on the cable; and means whereby the car and cable are also interlocked against relative vertical movement.

8. In a cable-haul, the combination with the cable and a car, depending dogs on the car, means on the cable engaged by said dogs, and means fixed along the track for engaging a dog to raise it out of operative position. 125

9. In a cable-haul, the combination of the cable and the car, dogs depending from the car, means on the cable engaged by the dogs, and a 130

plurality of lifting means along the track each effective as to one dog independently of the other.

10. In a cable-haul, the combination of the cable, and the car to be held thereby, dogs depending from the car, means on the cable to be engaged by the dogs, and a lifting-rail located along the track in position to engage a dog and raise the latter out of operative position.

11. In a cable-haul, the combination of the cable and the car to be held thereby, dogs depending from the car, means on the cable to be engaged by the dogs, and a lifting-rail located along the track in position to engage a dog and raise the latter out of operative position; said rail being located to one side of the path of the dog, and said dog having a lateral projection which rides upon the rail to lift 20 the dog.

12. In a cable-haul, the combination of the cable, the car to be held thereby, dogs depending from the car, means on the cable engaged by the dogs, lifting-rails alternated on opposite sides of the dogs, and a lateral projection on the side of each dog toward the lifting-rail which is to control the dog.

13. In a cable-haul, the combination of the cable, the car, interengaging means on the cable and car, and means automatically actuated by the cable for retarding the car.

14. The combination of the cable, the car, a brake-shoe engaging a part of the car to retard the car, and means whereby the cable 35 moves said brake-shoe into braking relation with the car.

15. In a cable-haul, the combination of the cable, the car, interengaging and interlocking means carried by the cable and car to prevent 40 their relative movement as the car is being held, means whereby said interlocking means are permitted to move out of interlocked relation, and automatic means for causing relative movement between the cable and the car 45 to cause said interengaging means to move out of said interlocked relation.

16. In a cable-haul, the combination of the car having depending dogs, the cable having means with which said dogs engage and become interlocked by relative movement in the direction of the trackage, means for lifting one of said dogs to permit said parts to move out of interlocked relation, and means for causing relative movement between the car and the cable in the direction to cause disengagement of the interlocked parts.

17. In a cable-haul, the combination of the car having depending dogs, the cable having means with which said dogs engage and become interlocked by relative movement in the direction of the trackage, means for lifting one of said dogs to permit said parts to move out of interlocked relation, and means for causing relative movement between the car and the cable in the direction to cause disengagement of the interlocked parts.

18. In a cable-haul, the combination of the car having depending dogs, the cable having means with which said dogs become interlocked, means for lifting one of said dogs to permit unlocking of the other dog from the cable, a brake for retarding the car and pressure-applying means for said brake impinged by a part on the cable.

19. In a cable-haul, the combination of the car having depending dogs, a block on the cable with which said dogs interlock, said dogs being spaced apart to permit one of them to be elevated while the other is interlocked, a lifting-rail engaging one of said dogs to raise it, brake-shoes impinging the car-wheels to retard the car, pressure-plates for imparting pressure to said brake-shoes, and projections carried by the cable impinging said pressure-plates.

20. In combination with a cable-haul system employing dogs for establishing driving connection between the cable and the car; in combination with a delivery-section of track and a pick-up section of track, and means extending over the pick-up section for preventing engagement of a dog in the driving connection until a desired point is reached by the car.

21. In a cable-haul, the combination with a delivery-section of track downwardly inclined to deliver cars by gravity, a pick-up section of track adjacent to which the cable is run, and which is upwardly inclined to reduce the momentum of the cars; of dogs for establishing driving connection between the cable and the car, and means for preventing engagement of a dog in opposition to the momentum of the car.

22. In a cable-haul system, the combination of a cable, a pair of dogs on the car independently movable into and out of position to engage the cable and means for moving and holding each dog out of engaging position independently of the other dog.

23. In a cable-haul, the combination with dogs depending from the car; of a rail engaging the dogs to raise them and detents for holding said dogs in elevated position.

24. In a cable-haul, the combination with dogs depending from the car; of a rail engaging the dogs to raise them, detents for holding said dogs in elevated position while they are passing over a portion of the track, and means for releasing said detents to permit the dogs to assume operative position when the car has reached another portion of the track.

25. In a cable-haul, the combination with dogs depending from the car; of a rail engaging the dogs to raise them, detents for

holding said dogs in elevated position, laterally-disposed rails out of the path of the dogs but in the paths of the detents, engaging said detents and causing them to release the dogs.

26. In combination with the dogs on the car, means for elevating said dogs, detents engaging the dogs to hold them in elevated position, counterbalance-arms carried by the de-

tents and rails interposed in the paths of the counterbalance-arms.

The foregoing specification signed this 14th day of May, 1904.

JOHN L. WAGNER.
